UNITED STATES PATENT OFFICE.

WILLIAM J. MILLER, OF SULPHUR, LOUISIANA, ASSIGNOR TO C. H. REED, OF HOUSTON, TEXAS.

ROTARY BACK-UP POST.

Application filed January 3, 1922. Serial No. 526,615.

To all whom it may concern:

Be it known that I, WILLIAM J. MILLER, a citizen of the United States, and resident of Sulphur, Louisiana, have invented certain new and useful Improvements in Rotary Back-Up Posts, of which the following is a specification.

The invention relates to well drilling apparatus and particularly to what is known as a back-up post which is used on the "rotary" in the operation of unscrewing one drill stem section from another, the post being employed to apply power to the wrench or tong for rotating one stem section in relation to the next adjacent section above while the latter is anchored, by another tong, to a part of the derrick.

In the drawings

Figure 1 is a view of the invention in side elevation.

Fig. 2 is an edge view at a quarter turn from Fig. 1.

Fig. 3 is a view in the nature of a diagram of a "rotary" with the invention in place.

In these drawings, 1 is the post, the lower end of which is adapted to be seated in an opening or socket in the "rotary". The upper portion of the post is slotted at 2 and 30 the walls are extended to form ears 3 in which is mounted a pin 4 forming a pivot for a latch 5, which holds the post section or extension 6 in upright position. This extension or member 6 is pivoted about mid-way of its length on a pin 7 extending between and supported by the upper walls or ears 8 of the post and the lower end of the pivoted member 6 is reduced and engages a notch 9 in the upper edge of the latch. The 40 latch is pressed upwardly by a spring 10. Its end 12 extends out beyond the post so as to be readily accessible to pressure or to the blows of a hammer so that it may be depressed readily to release the pivoted bearing member 6, which latter may then fall into the position shown in dotted lines.

This post is used on the rotary table as a means for driving a heavy chain or other pipe tong *b*, gripping the drill stem below a joint to be broken or unscrewed. The practice is to attach a heavy tong *C* to the drill stem above the joint to be broken, the said tong being anchored by a cable to a leg of the derrick. This tong holds the upper portion of the drill stem in a rigid position.

Rotation of the rotary brings the back-up post against the handle of the tong which is on the drill stem below the joint and its rotation unscrews the joint to be broken. After the joint has been unscrewed, the back-up post, of course, is very tightly pressed against the handle of the lower tong. Where the practice has been to use a plain solid steel bar for a back-up post, it has been necessary to do heavy sledging to release the friction of the tong handle against the back-up post. This is heavy labor for the men and a great amount of time is consumed in releasing the tong.

With the present invention the back-up post would be brought by the rotary around so that the upper pivoted bearing member latched in its upright position will engage the lower tong or wrench and transmit thereto from the rotary the necessary power to break the joint by unscrewing the parts. Then, after the rotary has been stopped, the projecting end of the latch will be hit with a hammer, driving it downward against the pressure of its spring, thus releasing the pivoted bearing or pressure transmitting pin 6 and this member then will drop back freeing the back-up tong handle, enabling the tong to be readily removed.

For unscrewing the next joint the bearing or pressure member will be lifted to upright position and the operation repeated.

The back-up post is held in its operative position by a taper key 11 which is seated in a groove 12 of the post having an inclined bottom 13.

The upper part of the post is off-set laterally from the lower part so that the pivoted section or arm 6 is located to one side of the vertical axis, and when the arm 6 is in contact with the arm of the tongs, the whole back-up post will be prevented from turning out of its working position.

The use of this back-up post will avoid the necessity of reversing the rotary. This involves heavy labor on the part of the men on the derrick, and is objectionable for other reasons.

I claim:

1. A back-up post for the rotary of well drilling apparatus comprising a main portion furnishing a support and a bearing member at the upper part of said support pivoted thereto to one side of the vertical axis thereof, and means for holding the

- bearing member in substantially upright position, substantially as described.
2. A back-up post for rotary drill apparatus consisting of a main portion to be mounted on a rotary, a bearing or pressure member pivotally mounted at the upper part of said post, and a latch for holding the said member in substantially an erect position to bear on the handle of a wrench mounted on a drill stem section, said latch engaging the lower end of the pivoted bearing member, and releasing the same when forced downwardly.
3. A back-up post for the rotary of well drilling apparatus comprising a main part, a bearing section pivoted to the upper part thereof, and a latch pivotally mounted and extending substantially transversely of the
- post engaging the lower end of the pivoted bearing section to hold it substantially erect, 20 and having an end accessible to pressure for forcing it into position to release the pivoted bearing section, substantially as described.
4. A back-up post for the rotary of well 25 drilling apparatus having an upper portion off-set from the lower portion, a member pivoted in the upper off-set portion whereby it lies eccentric to the vertical axis of the post and a latch for holding said member 30 in upright position, substantially as described.

In testimony whereof, I affix my signature:

WILLIAM J. MILLER.
